UNITED STATES PATENT OFFICE.

JOSEPH G. JOHNSTON, OF DETROIT, MICHIGAN, ASSIGNOR TO THE AMERICAN CAR & FOUNDRY COMPANY, OF ST. LOUIS, MISSOURI.

COPE-PATTERN.

SPECIFICATION forming part of Letters Patent No. 678,256, dated July 9, 1901.

Application filed December 13, 1900. Serial No. 39,691. (No model.)

To all whom it may concern:

Be it known that I, JOSEPH G. JOHNSTON, a citizen of the United States, residing at the city of Detroit, county of Wayne, State of Michigan, have invented a certain new and useful Improvement in Cope-Patterns, of which the following is a full, clear, and exact description, such as will enable others skilled in the art to which it appertains to make and use the same, reference being had to the accompanying drawings, forming part of this specification, in which—

Figure 1 is a top plan view of my improved cope-pattern, chill-ring, and flask. Fig. 2 is a vertical sectional view of the same, taken on line 2 2, Fig. 1, the same illustrating a sand matrix therein before the parts have been subjected to pressure. Fig. 3 is a vertical sectional view of a completed mold, showing the relative position of my improved cope, flask, and chill-ring to a drag-flask. Fig. 4 is a side elevational view of the same, showing the manner in which the parts are clamped together; and Fig. 5 is a detail elevational view.

This invention relates to a new and useful improvement in a cope-pattern, flask, and chill-ring, the same being designed particularly for use in the formation of the sand matrix for the flask of the cope side of a mold for casting car-wheels.

One object of my present invention is to produce a pattern, flask, and chill-ring of the character described which is effective, comparatively light, strong, and susceptible of being handled and manipulated by a molding-machine such as is illustrated and described in an application filed by me July 9, 1900, serially numbered 22,987.

Another object is to form a cope side or flask of a mold with a sand matrix which will be complementary to a drag-flask and its sand matrix such as shown and described in an application filed by me December 13, 1900, said application being serially numbered 39,693.

With these objects in view the invention consists in the novel construction, arrangement, and combination of the several parts of my device, all as will hereinafter be described, and afterward pointed out in the claims.

To attain the objects to which I have above referred, I make use of the construction illustrated in the accompanying drawings, wherein like characters designate like parts throughout the several views.

In the drawings, M represents the chill-ring, N the skeleton flask, and O the pattern, all of which parts are employed to carry out my present invention. This chill-ring M has a slightly-conical inner face m, which blends into an enlarged recess m', formed in one edge of said ring, said face and recess being of a shape to conform to the tread and part of the flange, respectively, and consequently the throat of the car-wheel. The outer face of this chill-ring M is provided with trunnions m'', by which the same may be handled by the bail of a hoist or crane, and is also provided with lugs or ears m³ and m⁴, the former being provided with holes for receiving bolts or securing devices m⁵ for attachment to the flask N, while the latter is provided with pins m⁶, which engage in one operation perforated lugs or ears o⁸, formed on the pattern, and in another operation perforated lugs or ears formed on the drag-flask L, which latter operation occurs when a mold is formed ready to receive molten metal by arranging and clamping together the drag-flask L, chill-ring M, and the cope-flask N, as is illustrated in Figs. 3 and 4.

While I have illustrated and referred in this application to the drag-flask L, it forms no part of this invention, as it is the subject-matter of a separate application serially numbered 39,693, to which I have previously referred, the same being illustrated and briefly described here only for the purpose of making the construction and use of my improved cope pattern, flask, and chill-ring more clearly understood.

The pattern O consists of a face-plate o, properly shaped to conform to one face of a car-wheel, in the center of which is arranged a removable core-print o'. The face-plate is strengthened on its lower side by suitable strengthening webs or ribs o² and has a bottom plate o³, forming a reduced portion for fitting in an opening of a turn-table when practicing my invention in connection with the molding-machine forming the subject-

matter of application serially numbered 22,987, to which I have before referred.

5 o^4 indicates spring-seats projecting laterally from the pattern, four of such seats being preferably arranged equidistantly around the same. Springs o^5 are arranged in these seats and sustain an inverted cup or cap piece o^6 , serving as a follower and guide and also supporting the chill-ring M , as will herein-
10 after be described.

Bolts o^7 , passing through the cap-pieces and spring-seats, hold the springs under compression and limit the upward movement of the caps. In addition to the springs, the cope-
15 pattern is provided with lugs or ears o^8 , and in these are formed holes which receive the pins m^6 of the chill-ring. The cope pattern is further provided with stops o^9 , which meet the lower face of the chill-ring when said
20 cope pattern, chill-ring, and flask are being pressed, as will hereinafter be explained, making a uniform distance of travel and limiting the movement of the parts.

The cope-flask N consists of a skeleton
25 frame which is bolted or otherwise secured to the chill-ring M , and, as shown in Figs. 1 and 2, this cope-flask is made up of a plurality of three concentric rings n , connected by radially-disposed ribs or bars n' . The lower edges
30 of the two innermost of these concentric rings and radial ribs or bars are formed beveled or knife-like to enable the sand to pack uniformly therearound.

The skeleton cope-flask is so constructed
35 that it conforms to the contour of the pattern, both as to the sharp edges of the bars next the pattern and their upper edges.

When it is desired to make a sand matrix for my improved flask and chill-ring, the two
40 are placed upon the pattern O , as illustrated in Fig. 2. Sand is then poured through the skeleton flask onto the face-plate o , after which the sand is distributed over the pattern by a sweep (not shown) of such shape that it
45 will regulate the depth of sand required on the different parts of the pattern, so that all the molds will contain a uniform quantity of sand, it being understood that the parts are previously arranged in one of the openings
50 in the turn-table of the molding-machine, such as shown in application serially numbered 22,987, to which I have before referred. The turn-table being revolved until the flask, chill-ring, and pattern register with the press
55 is subjected to pressure by the press, which pressure forces the flask and chill-ring and the pattern toward each other and compresses the sand contained within the parts until further movement of the parts toward each other
60 is arrested by the contact of the lugs o^9 on the pattern with the under face of the chill-ring. Springs o^5 being now under compression will upon the release of pressure force the chill-ring and its carried flask away from the pat-

tern, carrying with them the pressed-sand 65 matrix. The chill-ring, flask, and its carried sand matrix are now removed from the pattern and are ready to be placed over and clamped to the drag-flask L and its carried sand matrix, as shown in Figs. 3 and 4, preparatory to receiving the charge of molten metal, it being understood that all necessary cores were placed in the drag portion of the mold before the cope portion was arranged thereover.

75 In Fig. 4, x indicates the core-print.

Fig. 5 shows the core V in position. U indicates the circular core supported on feet. u and u' are the chaplets for preventing the ring-core from floating. W indicates the cast-wheel.

I am aware that minor changes in the arrangement, construction, and combination of the several parts of my device can be made and substituted for those herein shown and described without in the least departing from the nature and principle of my invention.

Having thus described my invention, what I claim, and desire to secure by Letters Patent, is—

90 1. The combination with a pattern provided with pockets at points around its periphery, of springs arranged in said pockets for supporting a chill-ring, caps for the springs, and bolts passing through the caps and the bottom walls of the pockets, substantially as described.

95 2. The combination with a circular pattern, of recessed lugs o^4 extending laterally beyond the periphery of said pattern, said lugs being arranged on the bottom portion of the pattern, springs arranged in the recesses of said lugs for supporting a chill-ring, and stops on the pattern for engaging the chill-ring when the springs are compressed, substantially as described.

100 3. The herein-described pattern comprising a face-plate, a bottom wall, ribs connecting said face-plate and bottom wall, recessed lugs extending laterally from the pattern, and springs arranged in the recesses in said lugs; substantially as described.

105 4. The herein-described pattern whose body portion comprises a face-plate, side walls and bottom wall, interiorly-arranged strengthening-ribs, laterally-projecting recessed lugs which extend beyond the periphery of the body portion of the pattern, and springs in the recesses in said lugs for supporting the chill-ring; substantially as described.

110 In testimony whereof I hereunto affix my signature, in the presence of two witnesses, this 4th day of December, 1900.

JOSEPH G. JOHNSTON.
